CLAIM

The ornamental design for a display screen or portion thereof with graphical user interface, as shown and described.

DESCRIPTION

FIG. 1 is a front view of a first embodiment of a display screen or portion thereof with graphical user interface;

FIG. 2 is a front view of a second embodiment of a display screen or portion thereof with graphical user interface;

FIG. 3 is a front view of a third embodiment of a display screen or portion thereof with graphical user interface; and,

FIG. 4 another front view of the first embodiment of a display screen or portion thereof with graphical user interface, shown with a different broken line disclosure.

In the drawings, the broken lines are for the purpose of showing portions of the display screen with graphical user interface that forms no part of the claimed design.

1 Claim, 4 Drawing Sheets
